UNITED STATES PATENT OFFICE.

JOHN D. SAMMONS, OF HOT SPRINGS, ARKANSAS, ASSIGNOR OF ONE-HALF
TO JOHN J. SUMPTER, OF SAME PLACE.

LIFTING-JACK.

SPECIFICATION forming part of Letters Patent No. 242,735, dated June 7, 1881.

Application filed March 12, 1881. (No model.)

To all whom it may concern:

Be it known that I, JOHN D. SAMMONS, of Hot Springs, in the county of Garland, and in the State of Arkansas, have invented certain new and useful Improvements in Lifting-Jacks; and I do hereby declare that the following is a full, clear, and exact description thereof, reference being had to the accompanying drawing, and to the letters of reference marked thereon, making a part of this specification.

This invention has for its objects to provide a light, cheap, and effective lifting-jack for various purposes. These objects I attain by the device shown in the accompanying drawing, 15 in which is represented a vertical sectional view of my apparatus.

In the said drawing, the letter A indicates a hollow shaft or body, constructed of wood or any other suitable material, and mounted 20 on a base, B.

The letter C indicates a ratchet-bar arranged to be moved vertically within the hollow shaft or body, the teeth of which are adapted to engage the loose detent D, which is pivoted in a 25 suitable slot in the side of the shaft or body A. The upper end of the ratchet-bar is provided with a slotted head, in the slot of which is pivoted a lever, E, the upper end of which

is provided with a pivoted block, F, having a curved seat, G, which is placed under the object to be lifted.

It will be seen that by means of the ratchet-bar the apparatus may be adjusted to the height of the object, and held securely thereunder, after leverage may be applied by the lever E, so as to properly elevate such object.

Having thus fully described my invention, what I claim, and desire to secure by Letters Patent, is—

As a new article of manufacture, a lifting-jack composed of a hollow shaft or body, A, with a suitable base, B, a loose detent, D, and a ratchet-bar, C, to which is pivoted a lever, E, upon the upper end of which is carried an oscillating bearing-block, F, as and for the purpose set forth.

In testimony that I claim the foregoing I have hereunto set my hand this 26th day of March, 1880.

JOHN D. SAMMONS.
mark.
